FOREIGN PATENT DOCUMENTS

PH 3-2009-198-0001 * 4/2009

Primary Examiner — Paula Allen Greene(74) *Attorney, Agent, or Firm* — David W. Carstens;
Carstens, Allen & Gourley, LLP(57) **CLAIM**

The ornamental design for a teardrop tealight urn, as shown and described.

DESCRIPTION

FIG. 1 is a front view of a teardrop tealight urn;
 FIG. 2 is a rear view of a teardrop tealight urn;
 FIG. 3 is an upper perspective view of a teardrop tealight urn;
 FIG. 4 is a lower perspective view of a teardrop tealight urn;
 FIG. 5 is a right side view of a teardrop tealight urn;
 FIG. 6 is a left side view of a teardrop tealight urn;
 FIG. 7 is a top view of a teardrop tealight urn; and,
 FIG. 8 is a bottom view of a teardrop tealight urn.
 The portions of the tealight holder in FIGS. 1, 3, 4, 5, 6, and 7 that are not seen within the stated figures are disclaimed and form no part of the claimed design.
